(57) **CLAIM**

The ornamental design for a drip tray, as shown and described.

DESCRIPTION

FIG. 1 is a top view of the drip tray.

FIG. 2 is a side view of the drip tray, and all side views are the same.

FIG. 3 is a bottom view of the drip tray; and,

FIG. 4 is a top perspective view of the drip tray.

The broken lines depict portions of the drip tray and form no part of the claimed design.
